O. M. Rau
Attorney.

UNITED STATES PATENT OFFICE

OTTO M. RAU, OF PHILADELPHIA, PENNSYLVANIA

RADIO LOUD SPEAKER AND LAMP

Application filed May 17, 1927. Serial No. 191,994.

The object of my invention is to provide a construction of loud speaker for radio apparatus which may constitute a part of an electric standing or table lamp fixture and, more particularly, to constitute the shade thereof or to be so intimately positioned within the shade that it is unobtrusive or shielded, whereby the presence of the loud speaker is not suspected.

10 My object is further to so position the loud speaker as to elevation and position that direct sound vibrations are not transmitted from it to the persons present in the room, but, on the other hand, the perimeter of the 15 loud speaker shall so lie in a horizontal or substantially horizontal plane that the reproduction will reach the ear of those present in a subdued but clear and more natural effect than would be possible by the direct sound 20 vibrations.

My object is also to construct the loud speaker of a transparent or translucent material so that if the same constitutes the lamp shade proper or is interposed between the 25 lights and a surrounding lamp shade of ordinary construction, the luminosity from the lights through the loud speaker diaphragm will be effective and may eliminate the necessity for the ordinary lamp shade structure.

30 My object is further to so combine a lighting fixture with a loud speaker that the direct sound waves from the diaphragm of the loud speaker will be transmitted in a more or less vertical direction from both above and below 35 the diaphragm, and whereby the more subdued lateral vibrations arising therefrom will effectively reach the ears of those present and occupying positions at the sides of the lamp fixture.

40 My object is also to combine a loud speaker disk or diaphragm with heating means whereby it retains its tension and responsiveness to rapid vibration, irrespective of the humidity 45 conditions of the surrounding air.

With the above and other objects in view, the nature of which will be more fully understood from the description hereinafter, the invention consists in the novel construction of 50 radio loud speaker and lamp, as hereinafter

more fully described and defined in the claims.

Referring to the drawings: Fig. 1 is a side view, with part in section, of a standing lamp and shade with my improvements applied thereto; Fig. 2 is a similar view of a table lamp, but showing a modification of my invention; Fig. 3 is a diagrammatic view illustrating the arrangement of the electric circuits of the lamp and loud speaker features 55 embodied in my improvements; and Fig. 4 is an elevation of a modification of my invention.

Referring to Fig. 1, 2 is the upright stand or pedestal and may be of any suitable construction such as is commonly employed in electric standing lamps. By way of illustration, the electric equipment of the lamp is indicated by the lamp sockets 3, 3, and the electric bulbs 4, 4, the same being attached by 60 suitable coupling means with the upper part of the stand 2.

Secured at the upper part of the pedestal 2 above the electric bulbs is a bracket 6 upon which is supported the frame 5 of the operating vibrating mechanism of the loud speaker, the same having a connection with the center of the vibrating diaphragm 7 thereof by the usual means 8.

The loud speaker proper is of a more or less flattened cone-shaped disk and is suspended from the parts 5 and 6 by the connection 7a, or in any suitable manner, so that its vibration is not interfered with. As shown, this cone-shaped disk is arranged with 85 its greatest diameter in a horizontal plane so that, in a measure, it simulates a lamp shade over the electric bulbs.

As a further feature of my invention, I may arrange above the loud speaker diaphragm 7, a lamp shade 15, the same being supported by a suitable bracket secured to the upper part of the pedestal. In the particular means shown, the angular arms 10, 11 and 12 extend from the bracket 6 and encircle 90 about the loud speaker disk 7 and unite in a central connection 13 immediately over the apex of the loud speaker and supporting the central portion 14 of the lamp shade 15 in any suitable manner. In this construction, 95 100

the supporting means and the lamp shade are entirely clear of the loud speaker diaphragm 7 to such an extent as to not interfere with its vibration.

- 5 The lamp shade 15 has its perimeter preferably above the perimeter of the loud speaker disk and, for shielding purposes, the lamp shade may be provided with a downwardly extending fringe 16 which, while shielding 70 the loud speaker from view, does not interfere materially with the propagation of the sound vibrations in a more or less horizontal direction from the perimeter of the loud speaker. It will be understood that the perimeter 9 15 of the loud speaker 7 may be attached directly to the bracket 10 where the same is used to support the lamp shade. In this construction, the lamp shade may be of any shape desired, although for purposes of illustration, 20 it is indicated as corresponding in shape to the cone-shaped disk of the loud speaker.

In the construction shown in Fig. 2, 2a is a table lamp base of any suitable ornamental shape and provided with the upright pedestal 25 extension 2 for supporting the electric lights, as before explained, and in this illustration, the loud speaker conical disk 7 is sustained at its perimeter by a light open bracket structure 15a from the perimeter of which a light 30 fringe 16 may depend to give to the conical loud speaker disk the effectiveness in design to a lamp shade. In this case, the disk 7 may be of translucent material, such as varnished paper, and may be ornamented artistically 35 in any manner desired, so that the light from the electric lamps may be transmitted through it with artistic results.

The presence of the electric lighting means of the lamp disarms the observer from the 40 supposition that the fixture is anything but a lamp itself, and the same is also true of the construction shown in Fig. 1.

By arranging the loud speaker with its perimeter lying in a horizontal plane, the 45 sound transmission is more subdued and clearer than where the loud speaker has its large diameter arranged in a vertical plane, as commonly employed. In the present construction, the more intense vibrations, 50 parted to the air are transmitted in a vertical direction downward to the floor or table and are reflected back in an upward direction with the attendant travel laterally of the sound waves, which greatly improves the results to the listener who is naturally positioned to one side of the loud speaker and more or less in a horizontal plane of its largest diameter.

In Fig. 3, I have indicated the various electric circuits which would be employed in connection with the combined lamp and loud speaker illustrated in Figs. 1 and 2. The radio vibrator for operating the loud speaker would be energized by the current received 65 through the vertical wires 19 and the flexible

conductors 20 leading to a suitable connecting plug 22. The electric lighting circuits are indicated at 17 with the flexible conductors 18 likewise supplied with a suitable connecting plug 21. These extending conductors are 70 indicated at 18 and 20 in Figs. 1 and 2, but I do not limit myself in any respect to the particular electrical connections, as it is manifest that, if desired, the electric wiring of the combined lamp and loud speaker may terminate in sockets on the lamp pedestal and with which flexible conductor cords may be suitably coupled.

In Fig. 4, I have shown a modification of the assembly of the electric lighting, the loud speaker and the lamp shade in respect to their mutual attachment and support and by which the several parts may be adapted to a tall stand as in Fig. 1, or to a low table lamp structure as in Fig. 2. It will be noted that 80 in Fig. 1, the lamp supporting means for the shade is of an extended nature formed by the bar portions 10 and 11 surrounding the loud speaker 7, whereas in Fig. 2, the fringe of the shade frame is secured within and below the 85 loud speaker. In the modification shown in Fig. 4, the loud speaker 7 and its operative parts 8 and 5 are brought further down toward the sockets 3 of the electric lights, thereby greatly reducing the intermediate portion 90 6, and the support for the shade 15 is extended upward through the loud speaker to provide a central means of attachment for the shade. More specifically, the shade 15 may be made 95 as shown in Fig. 1 and has its central wire 100 portion 14 secured to a Y shaped central connection 13 having its lateral arms 11a extended downward through apertures 7b in the loud speaker and connected to the casing or frame 5 containing the electro-magnetic 105 means for operating the loud speaker, said 110 means for operating the loud speaker, said casing itself directly connected through the part 6 with the stand or support 2. It will be seen from Fig. 4, that the mechanism embodied in this assembly is very compact and simple. As further explanation, it will be seen that the inverted U shaped structure formed by the parts 11a and 13 has its lateral arms extended downwardly and detachably 115 secured in place by screws 5a. By reason of this construction, the loud speaker 7 may be positioned upon its supporting and vibrating means 5 and thereafter the shade support connected in position as shown.

As a further feature of my construction 120 shown in Fig. 4, the part 2 may be disconnectible from the lower part 2b of the stand and the electric conductors 18 and 20 respectively having terminals 21 and 22 may extend from the part 2 for convenient connection with the radio cabinet. In this connection, the upper part of my improved loud speaker lamp may be adjusted to any other position in the room adapted to receive it, or, in fact, it may be held in the hand, and in that case the lamp 125 130

shade 15 may be removed from its support 13.

The diaphragm or disk of the loud speaker being arranged over the electric lights, is caused to be heated to such an extent as will insure it against sluggishness in sound vibrations which otherwise is caused by atmospheric changes in humidity. This heating of the diaphragm or disk keeps it in a fine state of tension, so as to be very responsive to slight vibrations, and consequently effective in reproduction of the higher overtones.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim and desire to secure by Letters Patent is:

1. An upright support adapted to stand upon the floor or table provided at its upper portion with a cone-shaped loud speaker disk in which the largest diameter is arranged in a substantially horizontal plane, the said support extending from a point below and close to the loud speaker whereat it is provided with electric lighting devices, to a point above the loud speaker disk for providing a supporting means for attachment of a shade.

2. The invention according to claim 1, wherein further, the loud speaker disk is provided with vibrating mechanism and with one or more apertures near its center and in which the support is extended through the apertures in the loud speaker disk without contact therewith and providing means for attachment of a shade.

3. The invention according to claim 1, wherein further, the upper end of the support extends through the central portion of the conical end of the loud speaker, said extended support providing means for attachment of a shade.

4. The invention according to claim 1, wherein further, the loud speaker is provided with vibrating mechanism and the upper end of the support is extended to a position above the cone-shaped loud speaker and adjacent to the axis thereof, said support having a connection with the frame containing the vibrating mechanism for the loud speaker and also providing a supporting means for attachment of a shade.

In testimony of which invention, I hereunto set my hand.

OTTO M. RAU.
